CLAIM

The ornamental design for suspenders for animal footwear as shown and described.

DESCRIPTION

FIG. 1 is a perspective view of suspender straps showing our new design;

FIG. 2 is a front view thereof;

FIG. 3 is a back view thereof;

FIG. 4 is a right-side view thereof;

FIG. 5 is a left-side view thereof;

FIG. 6 is a top view thereof;

FIG. 7 is a bottom view thereof; and,

FIG. 8 is another perspective view of the suspenders for animal footwear showing our new design being worn by a dog.

In the drawings, the equal-length broken line showing of the suspenders for animal footwear elements form no part of the claimed design. The broken lines showing a dog in FIG. 8 depict environmental structure that forms no part of the claimed design. All broken lines form no part of claim.
